UNITED STATES PATENT OFFICE

LUIGI M. SERRA, OF ROME, ITALY

RAIL JOINT

Application filed October 18, 1930. Serial No. 489,638.

This invention relates to certain new and useful improvements in rail joints, and the primary object of this invention is to provide a rail joint structure embodying certain new and useful improvements on that type of rail joint structure forming the subject matter of my co-pending application Serial No 453,266 filed under date of May 17, 1930.

The nature of my improvement will be best understood as described in connection in the drawings in which they are illustrated, and in which:

Figure 1 is a side elevational view of a joint embodying the features of the present invention.

Figure 2 is a top plan view thereof.

Figure 3 is an elevational view looking at one side of the joint, the joint plate being removed for more clearly illustrating the 20 contractable element arranged between the joint plate and rail ends.

Figure 4 is a vertical transverse sectional view taken substantially on the line 4—4 of Figure 3.

Figure 5 is a perspective view of the contractable member forming a part of the invention.

Figure 6 is a perspective view of one of the joint plates.

Figure 7 is a similar view of the other of the joint plates.

With reference more in detail to the drawings, it will be seen that the rail heads are shown at 1, the rail webs at 2, and the rail base flanges at 3.

The ends of the rails to be spliced, rest on a bridge or reinforcing plate 4, the same being of the identical construction shown, and described in detail in my above identified co-pending application, and as herein shown, the bridge plate 4 is supported between two rail ties 5 and suitably retained in position thereon through the medium of spikes 6. The bridge plate 4 has depending from an intermediate portion thereof a strengthening rib 4', said rib 4' tapering toward its lower end. In cross section plate 4 and strengthening rib 4' resemble an inverted rail as suggested in Figure 4.

The joint plates are indicated by the ref-

erence characters 7 and 7' respectively. These joint plates span directly across the abutting ends of the rails, each including a thickened body portion 8 extending parallel to the abutting ends of the rails, and said body portion at the lower end of the joint plate being provided with a longitudinally extending socket or groove 9 adapted to receive therein corresponding edge portions of the rail base flange 3 and bridge plate 4 as suggested in Figure 4.

Above its groove or socket 9 the joint plate 7 is provided in the thickened portion 8 thereof with a pair of spaced transverse bolt accommodating holes 10 the bores of which are non-threaded.

The joint plate 7' above its channel 9 has its thickened portion 8 provided with a pair of spaced threaded sockets 11 for alignment with the bores 10. Bolts 12 have their shanks for the major length thereof smooth, and at their free ends the shanks of the bolts are reduced and provided with screw threads 13. The bolts 12 have their shanks passed through bolt accommodating holes 10, through longitudinal slots 14 provided therefor in the webs 2 of the rails at the abutting ends of the rails, and the threaded ends 13 of the bolts are threadedly engaged with the sockets 11, so that upon tightening of the bolts the joint plates will be moved inwardly toward one another to securely retain the rail ends in joined relation with the bridge plate 4.

The heads of the bolts 12 on opposite sides of said heads are flattened to provide flattened faces 15, and the joint of plate 7 at its thickened portion 8 and on the outer face thereof is provided with an integral longitudinally extending rib 16. Thus it will be seen that when the bolts 12 have been threaded into the sockets 11 a sufficient distance, and the bolts so rotated as to have the flattened faces thereof parallel to the rib 16, joint plate 7 will be forced slightly outwardly upon expansion of the spring tube 19 so that the rib 16 will overlie the upper flat faces 15 and engage therewith for retaining the bolts against casual rotation.

Each of the joint plates 7 and 7' has its thickened portion 8 tapering vertically to terminate at the upper portion of the plate in a longitudinally extending flange 17 forming on the inner side of the plate adjacent the upper edge of the plate a longitudinally extending supporting shoulder 18.

As shown in the drawings, the spring tube 19 that is split longitudinally as at 20 is supported between the webs 2 of the rails, and the joint plate 7 and is supported through the medium of the shoulder 18 as suggested in Figure 4. It will be noted that the spring tube 19 spans directly across the abutting ends of the rails.

From the foregoing then it will be apparent that the bolts 12 engaging the sockets 13 secure the joint plates in operative position with respect to the abutting rail ends with the corresponding edge portions of the base flanges 3 and bridge plate 4 received within the grooves 9 of the joint plate thus securing the rails against movement relative to the bridge plate 4 and the member 19 will provide the necessary tension for retaining the rib 16 in engagement with the heads 15 to insure a locking of all the parts in the position suggested in Figure 4 and the parts are thus held against casual relative movement as may be caused by wear, vibration and the like.

Even though I have herein shown and described the preferred embodiment of the invention, it is to be understood that the same is susceptible of further changes, variations, modifications and improvements coming within the scope of the appended claims.

Having thus described my invention, what I claim as new is:

40. 1. A rail joint comprising in combination a joint plate adapted to be disposed parallel to the rail webs and spanning directly across the abutting ends of the rails, bolts passing through the joint plate and the rail webs, 45 an expandible and contractable tubular member interposed between said joint plate and the webs of the rails and spanning directly across the abutting ends of the rails, and said joint plate and bolts provided with co- 50 operating means for retaining the bolts against casual rotation.

55. 2. A rail joint comprising in combination a bridge plate adapted to lie beneath the abutted rail ends and to be supported and secured at each end on adjacent ties, a pair of joint plates respectively provided with a longitudinally extending channel adapted to receive therein corresponding edge portions of the rail base flanges and said bridge plate, 60 one of said joint plates provided with a plurality of threaded sockets, bolts passing through the other of said joint plates, the rail webs, and having threaded ends thread- 65 edly engaging said sockets, and an expansible member interposed between the rail webs

and the last referred to joint plates and spanning directly across the abutted ends of said rail.

3. A rail joint comprising in combination a pair of joint plates spanning directly across the abutted ends of the rails, one of said joint plates provided with a plurality of bolt accommodating holes, the other of said joint plates provided with a corresponding number of threaded bolt accommodating sockets, bolts extending through said bolt holes, the rail webs, and having threaded end portions threadedly engaging said bolt accommodating sockets, said bolts including heads having flattened faces and said first mentioned joint plates provided with an integral rib engageable with the heads of said bolts, and an expansible and contractable member interposed between the rail webs and one of said joint plates and acting oppositely on the rails and said joint plates.

4. A rail joint comprising in combination a pair of joint plates spanning directly across the abutted ends of the rails, one of said joint plates provided with a plurality of bolt accommodating holes, the other of said joint plates provided with a corresponding number of threaded bolt accommodating sockets, bolts extending through said bolt holes, the rail webs, and having threaded end portions threadedly engaging said bolt accommodating sockets, said bolts including heads having flattened faces and said first mentioned joint plate provided with an integral rib engageable with the heads of said bolts, and a tubular resilient member interposed between the rail webs and one of said joint plates, said tubular member being split longitudinally.

In testimony whereof I affix my signature.
LUIGI M. SERRA.
